STRAINER FOR WATER AND FLOUR THICKENING

Pearl E. Dillard, Denver, Colo.

Application January 9, 1956, Serial No. 39,656

Term of patent 14 years

(Cl. D62—2)

Figure 1 is a perspective view of the design for a strainer for water and flour thickening embodying my new design;

Fig. 2 is a side elevational view thereof; and

Fig. 3 is a bottom plan view.

I claim:

The ornamental design for a strainer for water and flour thickening, substantially as shown.
